LOCOMOTIVE STOKER

Nathan M. Lower, Crestwood, N. Y., assignor to
The Standard Stoker Company, Incorporated,
a corporation of Delaware

Application August 11, 1928, Serial No. 299,013
Renewed July 28, 1933

7 Claims. (Cl. 110—113)

This invention relates to mechanical stokers for locomotives, although it is not limited to that class of boilers and comprises mechanism for transferring the run-of-mine fuel from the tender 5 into the locomotive in a state suitable for economic firing.

It is an object of this invention to provide a stoker of the type that throws the coal into the fire box with more flexibility of control as 10 far as supplying fuel to the various areas of the fire bed than in previous designs.

Another object is to provide a simple device that will not get out of order easily, that will have few moving parts, and be of a rugged construction, to insure dependability and long life.

A further object of the invention is to charge fuel over the fire bed in small increments to secure the maximum efficiency in burning the coal.

These and other objects will be more readily 20 seen after reading the following description and appended claims in connection with the accompanying drawings.

In the drawings, Fig. 1 is a sectional view of the boiler and the stoker taken on the line 1—1 of Fig. 3 near the center line of the locomotive 25 and is somewhat diagrammatic, showing the buckets that throw the coal into the fire box; one bucket being in the lower position and one in the upper position.

Fig. 2 is a sectional view taken on line 2—2 of Fig. 4 near the end of the driving engine crank 30 shaft.

Fig. 3 is a plan view of the structure shown in Fig. 1, with the right side of the shovel box 35 and the conveyor trough shown in section.

Fig. 4 is an elevation view of the locomotive unit of the stoker, having some parts broken away to expose the rack and pinion that oscillate one of the throwing buckets.

Fig. 5 is a section taken through Fig. 4 on the line 5—5 showing the valve mechanism used for 40 controlling the rack and piston that operate the buckets, and is somewhat diagrammatic.

Fig. 6 is an enlarged section of a portion of the cylinder taken on line 6—6 of Fig. 5 showing the ports communicating with the piston valve.

Referring now to Fig. 1, within the conveying trough 1, which is flexibly connected at its forward end by the ball and ball clamp 42 to the 50 box 4 on the locomotive, a helical conveyor screw 2 conveys the coal forward to the mouth 3 of the practically air tight box or riser conduit 4 and moves the coal up the mouth 3 until it falls by gravity into the fuel throwing or projecting 55 buckets 5 and 6. By the term "bucket" through-

out this specification and in the claims herein-after made is meant a receptacle having sides and a bottom, as distinguished from a mere ram or piston. These buckets move upwardly through the coal in the lower end of the box 4 and inject 60 the fuel into the fire box. The box 4 is mounted on the back head of the locomotive and supported at the mouth of the box by a laminated leg 12 which is bolted to the locomotive frame; and allows sufficient movement of the stoker to take 65 care of the boiler expansion. The stoker is supported by the flanges 14 on the back head 11 so as to use the lower portion of the fire door opening 13 as an aerial passageway for the coal being projected into the fire box.

The bucket 5 is mounted on a square shaft 7 having round ends that journal in the side walls 9 of the box 4. A gear 8 is keyed on the shaft 7, beyond where it is journaled in the side wall 9 and meshes with a rack 10. Secured to the 75 rack, a piston rod 15 connects with the piston 16 which reciprocates in the cylinder 17. A port 80 as 82 and a similar port in the opposite end of the cylinder 17 alternately admit fluid pressure to opposite sides of the piston to reciprocate the piston and rack, and as the bucket 5 nears the end of its travel, the valve mechanism described herein-after acts to admit steam to the upper side of the piston 16, cushioning the forward movement of the bucket, starting it on its downward movement, thus allowing the coal to move freely into 85 the fire box.

As it is desired to scatter the coal to every part of the fire box, the buckets are set at a slight angle with the center line of the locomotive so 90 a greater area can be covered, and deflecting arms 18 and 19 are used to deflect a portion of the higher stratum of the coal to the extreme sides of the fire box. As shown the deflecting arms are hollow and have near their ends several jet holes 20 through which a blast may be made to issue by applying fluid pressure in the arms through the pipes 21 which extend up through the floor 22 of the box 4 midway between the buckets, and connect with the hubs 23 of the arms. The arms are pivotally mounted on the underside of the box cover 24 and are provided with extensions 25 and lock pins 26 for setting the vanes in various positions.

Some of the coal in the lower stratum is deflected to the rear corners with the aid of deflecting plates 30 and 31. Pipes 28 furnish fluid pressure to the jets 29 for blowing the coal to the rear corners. The cooling effect of the steam in the arms 18 and 19 and the distributor plates 105 110

30 and 31 prevents them from burning away quickly. The distributor plates are rigidly bolted to the inside wall 4b of the box 4 by the bolts 27 and are readily removable. The distributor plates 30 and 31 are set slightly above the lower wall of the fire door opening for admission of cooling air to aid in preventing their burning away.

The central stratum of coal passes between 10 these deflectors and naturally replenishes coal at the center and front corners. Thus the supplying of coal to any area of the fire bed is within the immediate control of the fireman and a stoker is herein provided with flexibility of control that meets the need for a device that can quickly replenish certain areas of the fire bed, as may often be required when operating with a shallow fire to secure the highest efficiency from the boiler.

20 The bucket is composed of a hub 74 and a curved outer surface 32 connected to the hub 74 by a radial wall 73 and side walls 76 extending from the entire curved surface to the hub.

The bucket is divided into two sections 71 and 25 72 by the wall 73 extending from the hub 74 to the curved wall 32. It will be noted that the portion 32a of the curved wall and the radial wall 73 and the sides of the bucket form a deep cavity into which the coal falls as it is discharged 30 from the forward end of the throat 3a.

The bucket moves slowly as it starts its upward stroke because the live steam port 82 is restricted at 82a (Fig. 6) and the end 75 of the curved wall 32a moves up through any overhanging coal without causing the coal to be thrown upward. As soon as the piston 16 moves past the large port 77 the bucket is uniformly accelerated to attain a speed at the end of its upward stroke sufficient to throw the coal to the front end 40 of the fire box. As the bucket swings upward the coal tends to move radially due to the centrifugal force but it is restrained in the bucket by the curved wall 32a. In Figure 1 is illustrated the position of the coal in bucket 6 as the bucket 45 swings upward and is about to discharge into the fire box.

The curved wall 32a plays a prominent part in receiving the coal and discharging it into the fire box. I find that the wall 32a is indispensable on such a throwing device because if a blade alone were used such as the radial wall 73 the centrifugal force would cause the coal to slide outward against the door 35 and the top 24 and be pulverized by the end of the blade crushing it 50 against the box. If the top of the box were made of a curvature similar to that of the bucket, a large amount of abrasion would occur, due to the fact that the centrifugal force would cause the coal to press forcibly against the inner surface 55 of the box 4.

Aside from the important function of making an air tight seal in preventing cold air from entering the fire box, the box is merely used for an enclosure for the buckets to prevent injury to the fireman and support the bucket shaft bearings and is not necessary as far as keeping the coal from being thrown out as the coal is held in the buckets by the curved ends 32a and the sides 76. The curved wall 32 of the bucket is used 60 to keep the bucket opening in the floor 22 of the box 4, closed as the bucket swings upward. The curved wall 32 and hub 74 and the sides 76 co-operate with sealing strips 33, 36, and 37 in preventing the leakage of fine coal dust, of which 75 ordinary run-of-mine coal contains a large per-

centage. Crimped springs such as 34 hold the sealing strips against the bucket.

The box 4 is provided with a door 35 for inspecting the enclosed mechanisms and removing any foreign material that may be lodged therein. A plate 40 is provided to cover the fore part of the box 4 and acts as a guard in preventing the coal which may be occasionally thrown too high from being thrown upward into the fire box, which would allow the draft to draw away a great deal of the finer particles. The plate 40 is easily removed and the deflecting arms 18 and 19 can be swung apart to permit an easy admittance to the fire box when boiler repairs are necessary. To effect an equal delivery of coal from the conveyor screw to the buckets 5 and 6, the flange 41 is provided with elongated bolt holes for allowing lateral movement of the ball clamp 42 for shifting the conveyor trough laterally as much as may be necessary. It will be noted that the conveyor 1 is set off center on Fig. 3 to offset the uneven delivery accompanying all conveyor screws. Using a left hand screw in this case, the greater portion of the coal will be delivered on the left. By setting the trough off center to the right, this 100 may be corrected. Swinging side wall sections 43, which function as fuel deflector vanes aid further in effecting an even supply to both buckets or they may be used to increase the supply to one bucket over the other by swinging both side walls 105 in the direction of the particular bucket.

The swinging side 43 is pivoted by a shaft 48, supported in the bearings 44 and 45 and is capable of being moved by locking member 46 after the nut 47 has been screwed off a considerable distance. The shaft 48 is made square near its end whereon is mounted the locking member 46 which has teeth 49 cooperating with similar teeth on the boss 57 in holding the swinging sides rigid in their various portions.

The locking member 46 fits on the squared portion of the shaft 48 and is made square at its upstanding central portion 46a with which a wrench may be used in moving the swinging sides. The nut 47 must be screwed down after 120 the adjustment is made to prevent the action of the coal in the throat of the box 3 from moving the sides.

The pistons 16 in the cylinders 17 that operate the buckets are alternately operated in timed 125 relation from a disc 50 mounted on an extension of the crank shaft of the engine 52 and enclosed by a case 53 bolted to the side of the engine so that some of the oil spray of the engine crank case, will enter and lubricate the mechanism 130 therein.

The disc 50 has a crank pin 54 that cooperates with a yoke 55 pivoted at 71 and attached at its lower end to a slide rod 56 in converting the rotary motion of the disc to reciprocating motion 135 at the slide rod 56. The slide rod is slidably mounted in the case 53 and extends to a point midway between the cylinder where its end 57 is turned up at right angle. The central portion 58 of a valve rod passes through the end 57 of 140 the slide rod and is spaced equally between the spacing collars 65 by the springs 66 and 67.

The cylinders 17 have valve casings 68 cast integral with them which have piston valves 70 acting therein for supplying steam to opposite 145 ends of the rack pistons 16.

The live steam is supplied to each cylinder by a pipe 80 provided with a valve located within easy reach of the fireman's seat. The exhaust steam is carried away by the exhaust pipe 81. 150

Porting as commonly found between such valves 70 and cylinders is employed here to furnish live steam to the piston as for example to the upper end by the port 82 leading to the very end of the 5 cylinder while the exhaust port 83 does not extend all the way to the end of the cylinder which furnishes the cushion for the piston and the bucket at the end of the stroke.

Live steam acts against the lower side of the 10 small head 84 of the valve 70 while a port 85 allows the steam to act also on the top side of the large head 86. A small duct 87 allows the steam to also act on the lower side of the large head 86.

As shown in Fig. 5 the valve is held in its upper 15 position because of the unbalanced pressure upwardly on the valve due to the steam acting on both sides of the large head and on the lower side of the small head, the upper side of the small head being vented to atmosphere.

20 The valve 70 is thus moved up and down entirely by the unbalanced condition of its heads. When the end 60 of the valve rod 58 is moved to the left the port 88 is opened to atmosphere which will exhaust the steam on the lower side of the 25 head 86 causing the valve 70 to be moved down by the steam acting on the upper side of the head 86. The ports 88 are larger than ports 87 and are set in from the end of the valve chamber to cushion the valve at the end of its stroke.

30 It is desirable to open the port 88 quickly to exhaust the steam from below the large head 86 of the valve faster than the steam can enter through the duct 87 so the crank pin 54 moves the yoke 55 only when traveling in its horizontal 35 quadrants. In other words the crank pin 54 reciprocates the valve rod 56 quickly from the position shown in Fig. 5 to a similar position on the other side of the center line of the yoke where it rests while the crank pin 54 is allowed to rotate due to the design of the inner face 89 of the 40 yoke 55.

The rod 59 at the opposite end of the valve rod 58 is shown in position to exhaust the port 89. Connected to the valve rod 59 is an eye bolt 95 45 smaller in diameter than the rod 59 so the steam may escape around it from the port 89. The eye bolt 95 is connected by a pin 96 to a lever 97 pivotally mounted to some convenient portion of the locomotive and moves back and forth with 50 the valve 59.

The main purpose of the lever is for manually operating the valve rods to cause the buckets 5 and 6 to operate when the engine 52 is not running. The rod 58 is allowed to slide through 55 the upturned end 57 on the slide rod 56 and compresses either the spring 66 or 67 depending upon the direction in which it is moved and is capable of operating the buckets regardless of the position of the rod 56, a door 98 is provided 60 in the deck of the locomotive so a fireman can use a grate shaker bar on the lever 97 for operating it. This lever 97 also serves the fireman as an indicator in showing him how fast the stoker is running.

65 The driving engine 52 as shown here is a low speed engine and the disc 50 is rotated directly by the crank shaft. The frequency of the bucket movements must be such to deliver fuel to the fire box as fast as it is being delivered into the 70 throat 3a of the box 4.

Gearing in a box 105 may be used in connection with the engine 52 to run the flexible drive shaft 106 the proper speed to feed the correct amount of coal to the locomotive fire box.

75 The flexible shaft 106 is flexibly connected at

its rear end to a rigid drive shaft upon which a pinion is mounted and meshes with a gear driving the conveyor screw 2. Such construction is well known and it need not be shown here.

From the foregoing it will be seen that I have 80 provided a stoker that delivers coal to a plurality of buckets that forcefully discharge it into the fire box through part of the fire door and that I provide a very flexible means for supplying fuel to any part of the fire box and that throughout the stoker is simple in construction and operation.

I claim:

1. In a locomotive having a firebox provided with a backhead having a firing opening; a plurality of oscillating swinging buckets for elevating fuel and discharging the same into the firebox through said opening, said buckets being mounted to swing in vertical planes which are inclined with respect to the medial vertical plane 95 of the firebox.

2. In combination with a locomotive having a cab deck and a firebox provided with a backhead having a firing opening above said deck, a casing in communication with said opening 100 and extending above and below said deck, a plurality of buckets pivotally mounted in said casing and arranged to oscillate in planes which are inclined with respect to the medial vertical plane of the firebox for elevating fuel through 105 said casing and discharging it therefrom through said firing opening into said firebox and means for imparting to said buckets a slow initial motion during their respective upward stroke and a rapid acceleration during the remainder of 110 their upward stroke.

3. In combination with a locomotive having a cab deck and a firebox provided with a backhead having a firing opening above said deck, a casing in communication with said opening and 115 extending above and below said deck, a plurality of buckets pivotally mounted in said casing and arranged to oscillate in planes which are inclined with respect to the medial vertical plane of the firebox for elevating fuel through said 120 casing and discharging it therefrom through said firing opening into said firebox, a conveyor conduit delivering fuel to said buckets, said buckets being arranged for alternately receiving fuel from said conduit and for alternately projecting 125 fuel into said firebox and means for imparting to said buckets a slow initial motion during their respective upward stroke and a rapid acceleration during the remainder of their upward stroke.

4. In combination, a firebox having a backwall 130 with a firing opening therein, a conduit communicating with said firing opening, and fuel projecting means adjacent the forward end of said conduit outside the firebox, and deflecting means pivoted in said conduit rearward of but 135 adjacent said fuel projecting means to be adjustable and movable inwardly of the conduit, said deflecting means comprising a pair of oppositely disposed deflector vanes pivotally mounted one at each side of the conduit on upstanding 140 axes and positioned to act on the fuel as it advances into the zone of action of the fuel projecting means.

5. In combination, a firebox having a backhead with a firing opening therein, a riser conduit 145 communicating with said firing opening, fuel projecting means mounted in said riser rearward of said backhead, and a pair of deflector vanes oppositely disposed adjacent said fuel projecting means and pivotally mounted one on each side 150

- of the conduit on upstanding axes disposed rearward of said fuel projecting means, the deflector vanes being wholly disposed without the firebox.
6. In combination, a firebox having a wall with an opening therein, a conduit communicating with said opening, said conduit being formed with a top, a bottom, and opposite upright sidewalls, fuel projecting means adjacent that end of said conduit which communicates with said opening, and a pair of deflector vanes oppositely disposed adjacent said fuel projecting means and pivotally mounted one at each upright side wall of the conduit on upstanding axes disposed rearward of said fuel projecting means, said vanes being wholly disposed without the firebox and arranged to swing inwardly of the conduit laterally across and over the conduit floor about said axes.
7. In combination, a firebox having a wall with an opening therein, a conduit communicating with said opening, said conduit being formed with a top, a bottom and opposite upright sidewalls, fuel projecting means adjacent that end of said conduit which communicates with said opening, and a deflector vane disposed adjacent said fuel projecting means and being pivotally mounted closely adjacent one of the upright side walls of the conduit on an upstanding axis disposed rearward of said fuel projecting means, said vane being wholly disposed without the firebox and arranged to swing inwardly of the conduit and laterally across and over the conduit floor about said axis.
